UNITED STATES PATENT OFFICE.

MARVIN C. SILVER, OF NEW BRUNSWICK, NEW JERSEY.

SPRING BED-BOTTOM.

SPECIFICATION forming part of Letters Patent No. 337,206, dated March 2, 1886.

Application filed September 30, 1885. Serial No. 178,652. (No model.)

To all whom it may concern:

Be it known that I, MARVIN C. SILVER, a citizen of the United States, residing at New Brunswick, in the county of Middlesex and 5 State of New Jersey, have invented certain new and useful Improvements in Spring Bed-Bottoms; and I do declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Figure 1 of the drawings is a representation of this invention, and is a top view. Fig. 2 is a longitudinal section. Fig. 3 is a detail, and shows the spring catch at the foot of the bed. Fig. 4 is a perspective view of the spring catch.

20 This invention has relation to spring-beds; and it consists in the construction and novel arrangement of devices, as hereinafter set forth, and pointed out in the claims.

25 In the accompanying drawings, the letter A designates the frame of the bed-bottom, which is usually of rectangular form, having the transverse head-bar B and the foot-bar C connecting the side rails, D D.

30 E is a middle transverse bar, which is secured to the lower portions of the side rails at about the middle portion of the bed-bottom. This bar serves as a bearing or support for the spiral springs F, which are secured 35 thereto, extending in series transversely along said bar from side to side of the bed-bottom, the tops of the springs being about level with the upper edges of the head and foot boards above mentioned. The tops of the springs F 40 are connected to a transverse wire, G, by means of loops a, formed on the upper ends of said springs, and the wire G is stayed in position by flexible fastenings H, which are attached to the side rails of the bed-bottom.

45 Upon the transverse wire G rests the middle portion of the bottom wires, K, which extend longitudinally, and are attached by their ends to short spiral springs L at the head and foot boards. The outer ends of these spiral 50 springs L are secured to the head and foot boards by means of staples, or in any proper

manner, while their inner ends are formed with loops to receive the looped ends of the bottom wires, K. Stay-wires N are also secured to the head and foot boards in connection with the spiral springs L. Each spring 55 L is provided with a stay-wire, which extends lengthwise and a little beyond the inner end of the opening, being then formed into a loop which encircles the bottom wire, which is attached to said spring. This loop b is made smaller than the spring L, and serves as a stop to prevent the spring from being extended by pressure beyond a certain distance. In this manner protection is afforded to the springs 60 to prevent them from being injured by undue pressure on any one of the wires. The adjustable head-rest P has side arms, c, and a transverse bar, d, connecting said side arms. To the bar d are attached the outer ends of the 65 wires e of the head-rest, their inner ends being looped, as at f, and connected by means of said loops to the short spiral springs g, which are attached to the edge portion of the transverse bar, usually to the same transverse bar 70 E which supports the spiral springs F. The side arms of the adjustable rest are pivoted to the side rails at h, and are provided with ratchet-arms k, which are pivoted thereto, and engage loop-catches l, secured to blocks or supports m on the inside of the side rails of the 75 bed-bottom. The ends of the pivoted ratchets are provided with cords n, which extend through bearings of the head-bar of the frame, and serve to afford means for disengaging the 80 ratchets from the catches when a readjustment of the head-rest is desired. The springs of the wires of the head-rest give sufficient play for the adjustment, tightening the wires as the rest is raised into higher position, and is liable to 85 be subjected to heavier strain.

To the foot-board are secured the spring-catches V in series, these catches extending along the outer face of the foot-board and having their spring tongues z turned upward and 90 then inward against the foot-board. By means of these spring-catches the bedclothes can be held in place at the foot with sufficient firmness to prevent the sleeper from disarranging them. At the same time they form no obstruction to the operation of making up the bed.

Having described this invention, what I

claim, and desire to secure by Letters Patent,
is—

1. The improved bed-bottom herein described, consisting of the longitudinal wires, the end springs connecting the said wires with the head and foot boards, the central transverse slat carrying spiral springs, the hinged head-rest having its wires connected to the said slat by spiral springs, and the transverse wire flexibly connected with the side rails of the frame, substantially as specified.
2. In a bed-bottom, the combination, with the

longitudinal wires supported by a series of middle spiral springs upon a transverse bar, of the pivoted head-rest having wires provided with spiral end springs attached to a transverse bar, pivoted ratchet-arms, and catches to engage the same, substantially as specified. 15

In testimony whereof I affix my signature in presence of two witnesses.

MARVIN C. SILVER.
